UNITED STATES PATENT OFFICE.

RUDOLF E. HELLMUND, OF PITTSBURGH, PENNSYLVANIA, ASSIGNOR TO WESTINGHOUSE ELECTRIC AND MANUFACTURING COMPANY, A CORPORATION OF PENNSYLVANIA.

DYNAMO-ELECTRIC MACHINE.

1,351,035.

Specification of Letters Patent. Patented Aug. 31, 1920.

Application filed December 14, 1915. Serial No. 66,725.

To all whom it may concern:

Be it known that I, RUDOLF E. HELLMUND, a subject of the Emperor of Germany, and a resident of Pittsburgh, in the county of 5 Allegheny and State of Pennsylvania, have invented a new and useful Improvement in Dynamo-Electric Machines, of which the following is a specification.

My invention relates to dynamo-electric 10 machines and systems of control therefor and especially to machines of the dynamotor type.

One object of my invention is to provide a machine of the above-indicated character 15 which shall be relatively simple and inexpensive in construction and effective and reliable in operation, and which shall embody means for effecting a variation of the voltage ratio between the two commutator 20 cylinders, or the equivalent, of the machine under predetermined conditions, either by simultaneously increasing the voltage of one cylinder and decreasing the voltage of the other or by maintaining the voltage of one 25 cylinder substantially constant and varying the voltage of the other cylinder, as herein-after more fully set forth.

More specifically stated, it is the object of 30 my invention to provide a dynamo-electric machine having a rotor provided with a plurality of commutator cylinders, a stator frame having a plurality of wound main and auxiliary polar projections, and a plurality of sets of brushes disposed upon the 35 respective cylinders in such manner that the voltage between brushes on one cylinder shall be proportional to the sum of the main and the auxiliary polar fluxes, and the voltage between brushes on the second cylinder 40 shall be proportional to the main flux.

A further object of my invention is to provide a system of control embodying a machine having the above-indicated characteristics, whereby, under regenerative conditions of a plurality of parallel-related 45 main dynamo-electric machines, the excitation of the field windings thereof may be automatically varied oppositely to the variations of armature or load current, thus 50 providing a stable regenerative system.

In connection with regenerative systems and in various other cases, it is often desirable to obtain from a relatively high supply-circuit voltage a low excitation volt-

age, and the well-known type of dynamotor 55 is generally employed for such purposes. The dynamotor has various advantages over an equivalent motor-generator set by reason of its lightness of weight and relatively low cost, and also because it is, at times, desirable to have the secondary voltage, that is, the lower voltage, of the dynamotor respond rapidly to any change in the primary voltage. The desired rapidity is possible only when the field fluxes that induce the primary and the secondary voltages are identical, as is the case in a dynamotor. However, the standard dynamotor has the disadvantage that it does not permit of a 60 change of the ratio of its high and low voltages. In some instances, it may be desirable to provide a rising-voltage characteristic in the output or low-voltage circuit of the dynamotor and, in other cases, to supply a 65 constant-voltage characteristic.

According to my present invention, I provide a novel type of dynamotor or double-commutator machine for effecting, in one case, a simultaneous opposite variation of the high and low voltages of the machine, 70 under predetermined conditions; or, in accordance with another modification, the voltage of the motor or high-voltage commutator cylinder is maintained substantially constant while the voltage of the generator or low-voltage commutator winding is automatically varied in the desired manner.

The standard type of dynamotor employs a plurality of main polar projections and a 75 plurality of commutating polar projections, the sets of brushes on the respective commutator cylinders being disposed in alignment with the commutating polar fluxes, in accordance with familiar practice. In accordance with certain features of my present invention, I so dispose the main polar projections and a plurality of auxiliary or secondary polar projections that certain of their respective axes are located intermediate spaced pairs of non-corresponding brushes; that is, the brushes on the different cylinders.

In the accompanying drawing, Figure 1 is a diagrammatic view of a dynamo-electric machine constructed and connected in accordance with my invention, the machine being shown in end elevation; and Fig. 2 is

a diagrammatic view, in side elevation on a smaller scale and with parts broken away, of the machine shown in Fig. 1.

Referring to Fig. 1 of the drawing, the 5 system shown comprises a plurality of suitable supply-circuit conductors respectively marked "Trolley" and "Ground", a variable translating device TD; and a dynamo-electric machine D of the general dyna- 10 motor type.

The translating device TD may comprise 15 a plurality of lamps or resistors or other devices which may be connected in or cut out of circuit, as may be desired, whereby a variable load may be introduced into the circuit of the low-voltage armature winding of the dynamotor, as more fully set forth hereinafter.

The dynamotor D comprises a rotor R 20 that is provided with a motor or high-voltage commutator cylinder M and a generator or low-voltage commutator cylinder G that are preferably disposed at the respective ends of the rotor and are connected, in the 25 usual manner, to a plurality of separate armature windings that are here diagrammatically shown at AW1 and AW2 in Fig. 2. A stator frame SF2 is provided with a plurality of oppositely-disposed main 30 polar projections MP1 and MP2, and a plurality of auxiliary polar projections or secondary projections AP5 and AP6 that are disposed in non-quadrature relation to the main projections MP1 and MP2; and a plurality 35 of suitable field-magnet windings MF1 and AF1 are disposed upon the main projections and the auxiliary projections, respectively.

The circuit of the shunt field winding 40 MF1 is established from the Trolley through a junction-point 10, the field winding MF1 and a junction-point 11 to the negative supply-circuit conductor Ground. The junction-points 10 and 11 are also directly connected to the brushes 1 and 2, respectively, 45 of the motor commutator cylinder M.

The auxiliary field winding AF1 is connected in series-circuit relation with the brushes 4 and 3 of the generator commutator cylinder G and the variable translating device TD.

The motor commutator cylinder M is provided with a set of suitable brushes 1 and 2, and the generator commutator cylinder G 55 is also provided with a set of brushes 3 and 4. Instead of the brushes being alined with each other, the pairs of non-corresponding brushes are shifted with respect to each other and the main polar projections have 60 their axis lying intermediate such spaced pairs. For example, in the system shown, the axis of the main polar projections extend through a point intermediate non-corresponding brushes 1 and 4 and a second point intermediate the non-corresponding

brushes 2 and 3. However, the auxiliary polar projections have their axis disposed in substantial alinement with the brushes 1 and 2 that are associated with the motor commutator cylinder M, and thus, the auxiliary 70 polar projections make an angle with the corresponding main polar projections that is materially less than 90 electrical degrees.

The main field winding MF1 is disposed around the main polar projections MP1 and MP2 in such manner as to produce north and south poles of magnetism therein, as indicated by the letters n and s, respectively. The circuit of the auxiliary field winding AF1 is disposed upon the auxiliary polar 80 projections AP5 and AP6 to create north and south magnetic poles in accordance with the designations n' and s', respectively.

It will be observed that, since the polar projections MP1 and AP5 provide north 85 magnetic poles, the flux threading the armature winding AW1, that is associated with the motor commutator cylinder M, is proportional to the sum of the main and auxiliary polar fluxes, while the flux linking 90 with the armature winding AW2, which is associated with the commutator cylinder G is proportional to the main polar flux by reason of the fact that the auxiliary polar flux passes parallel to the brushes 3 and 4. 95

The advantages of the construction just described may be set forth as follows: In other types of dynamotors, the primary armature winding, that is, the armature winding that is associated with the motor commutator cylinder M, is not used to as good advantage as possible, because the voltage induced between the motor commutator cylinder brushes 1 and 2 is the difference between certain positive and negative voltages 105 that respectively correspond to the various field fluxes, thereby requiring the use of a relatively large number of conductors to produce a certain total voltage. In the structure that is illustrated in Fig. 1, however, the auxiliary polar projections AP5 and AP6, by reason of their alinement with the brushes 1 and 2, serve as commutating poles therefor. Consequently, the auxiliary polar projections exert no direct effect upon 110 the voltage between the brushes 1 and 2 but serve to increase the voltage between the other brushes 3 and 4 with an increased load current in the translating device TD.

In this way, I provide a dynamotor in 120 which the motor voltage is maintained substantially constant, while the generator voltage is varied in accordance with predetermined conditions to thus vary the voltage ratio of the two commutator cylinders. 125

In Fig. 1, clockwise rotation was assumed, as indicated by the arrows, and the disposition of the main and auxiliary field windings with respect to the sets of brushes was determined in accordance with such direc- 130

tion. If rotation in the counterclock-wise direction is assumed, in general, the polarity of the auxiliary polar projections must be reversed or the relative locations of the various sets of brushes must be interchanged. It is believed that the foregoing statement will be evident to those skilled in the art without requiring any further illustration or description.

10 It should be noted that, although I have shown and described a machine having two commutator cylinders, my invention is capable of wider application; and a machine having a single armature winding and a 15 single commutator cylinder with a double set of brushes, or the equivalent, may be utilized.

Moreover, if desired, field-magnet windings of the familiar distributed type may 20 be employed instead of the concentrated or polar field-magnet windings that are illustrated, as will be understood.

I do not wish to be restricted to the specific circuit connections or structural details 25 and arrangement of parts herein set forth, as various modifications thereof may be made without departing from the spirit and scope of my invention. I desire, therefore, that only such limitations shall be imposed 30 as are indicated in the appended claims.

I claim as my invention:

1. In a dynamo-electric machine, the combination with a rotor having a plurality of windings and commutators therefor, of a 35 plurality of spaced sets of brushes for said commutators, and a stator frame having a plurality of main and auxiliary polar projections, the axes of all the main projections lying intermediate the commutating 40 zones of spaced pairs of non-corresponding brushes and the axes of said auxiliary projections substantially coinciding with the commutating zone of one set of said brushes.

2. In a dynamo-electric machine, the combination with a rotor having a motor and a 45 generator winding and commutators therefor, of a plurality of spaced sets of brushes for said commutators, a plurality of main polar projections having their axes lying 50 intermediate the commutating zones of a spaced pair of non-corresponding brushes, and a plurality of auxiliary polar projections having their axes substantially coinciding with the commutating zone of one set 55 of said brushes and respectively intersecting the axes of the corresponding main polar projections at an angle materially less than ninety electrical degrees.

3. In a dynamo-electric machine, the com-

bination with a rotor having a motor and 60 a generator winding and commutators therefor, of a plurality of spaced sets of brushes for said commutators, and a stator frame having a plurality of main polar projections having their axes lying intermediate 65 the commutating zones of spaced pairs of non-corresponding brushes, and a plurality of auxiliary polar projections mechanically and electrically related to said brushes in such manner as to perform the double function of aiding to vary the ratio of the voltages appearing at said sets of brushes and to act as commutating polar projections for the respective brushes on the motor commutator cylinder. 75

4. In a dynamo-electric machine, the combination with a rotor having a high-voltage and a low-voltage winding and a commutator for each of these windings, of a 80 plurality of spaced sets of brushes for said commutators, a stator frame having a plurality of polar projections and a plurality of sets of field windings to excite said projections and the rotor, means whereby the excitation of one of the sets of field windings is changed so as to increase the total voltage induced in the low-voltage winding without substantially changing the total field flux between the commutating coils of the high-voltage winding. 90

5. In a dynamo-electric machine, the combination with a rotor having coils located on a single core, and commutating means, of a plurality of spaced sets of brushes for said commutating means, one of said sets of 95 brushes acting as a motor brush set, and another set acting as a generator brush set, a stator core, a plurality of main polar projections and a plurality of materially smaller auxiliary polar projections, and a 100 plurality of sets of field-magnet windings located on said projections and respectively load-current-excited and shunt-excited only, said windings being mechanically and electrically related to said 105 brushes in such a manner as to induce fluxes of the same polarity only between the commutating zones of one set of brushes and a flux from only the main projections between the commutating zones of 110 the other set of brushes, whereby the excitation of only the auxiliary poles is inherently varied with the load of the machine.

In testimony whereof, I have hereunto subscribed my name this 10th day of Dec., 115 1915.

RUDOLF E. HELLMUND.
